(57) **CLAIM**

The ornamental design for a disposable kit for flow cytometer, as shown and described.

DESCRIPTION

FIG. 1 is a front elevational view of a first embodiment of a disposable kit for flow cytometer showing our new design; FIG. 2 is a rear elevational view thereof;

FIG. 3 is a left side elevational view thereof; and, FIG. 4 is a bottom plan view thereof.

FIG. 5 is a partially enlarged front elevational view of a portion of the design;

FIG. 6 is a rear elevational view thereof;

FIG. 7 is a left side elevational view thereof; and,

FIG. 8 is a right side elevational view thereof;

FIG. 9 is a top plan view thereof; and,

FIG. 10 is a bottom plan view thereof.

FIG. 11 is a partially enlarged front elevational view thereof along the line 11-11 of FIG. 5; and,

FIG. 12 is a cross sectional view cut along the line 12-12 of FIG. 11.

The dash-dash broken lines illustrate portions of the disposable kit for flow cytometer form no part of the claimed design. The dot-dash broken lines define boundaries of the claimed design and form no part of the claimed design. The disposable kit for flow cytometer is shown with symbolic breaks, formed by dot-dot broken lines. The appearance of any portion of the article between the break lines forms no part of the claimed design.
